UNITED STATES PATENT OFFICE.

ROBERT S. MEARS, OF ARKANSAS CITY, KANSAS.

DISTILLING AND HEATING APPARATUS.

1,358,091.

Specification of Letters Patent.

Patented Nov. 9, 1920.

Application filed January 2, 1919. Serial No. 269,255.

To all whom it may concern:

Be it known that I, ROBERT S. MEARS, a citizen of the United States, residing at Arkansas City, in the county of Cowley and State of Kansas, have invented a certain new and useful Improvement in Distilling and Heating Apparatus, of which the following is a specification.

My invention relates to improvements in distilling and heating apparatus.

One of the objects of my invention is to provide a distilling and heating apparatus which is simple in construction, cheap to manufacture and efficient in operation.

My invention provides further a novel boiler and novel means for heating water therein.

My invention provides still further novel distilling means by which water may be distilled and drawn off or automatically discharged back into the boiler when it is not being drawn off for use elsewhere.

The novel features of my invention are hereinafter fully described and claimed.

In the accompanying drawings which illustrate the preferred embodiment of my invention,

Figure 1 is a view partly in side elevation and partly broken away and in vertical section of my improved apparatus.

Fig. 2 is a view partly in end elevation, partly broken away and partly in vertical section of the apparatus.

Fig. 3 is an enlarged vertical sectional view of one of the check valves which are located in the pipes which discharge into the headers.

Similar reference characters designate similar parts in the different views.

1 designates the body of a horizontal boiler provided at its upper side with a vertical steam dome 2 and provided at opposite ends with heads 3, which are secured by bolts 4 to two peripheral annular flanges 5 secured respectively to the outside of the boiler adjacent to its ends.

Encircling the boiler 1 and spaced apart therefrom to form a flue space is a casing 6, which also is provided at its upper side with a smoke pipe 7, which encircles and is spaced apart from the steam dome 2. The casing 6 is provided below the boiler 1 with a vertical tubular extension 8 which forms a vertical passage communicating at its upper end with the flue space around the boiler.

At opposite sides respectively of the extension 8 are two headers, each consisting of a hollow cast member 9 to the outer side of which is secured by bolts 10 a cover plate 11. The header members 9 are respectively connected with the lower side of the boiler 1 by pipes 12. Inclined tubes 13 have their opposite ends respectively secured to the members 9 and interiorly communicating with the two headers.

The tubes 13 and the boiler 1 may be heated in any desired manner as by means of a gas burner 14 located in the extension 8 below the tubes 13, or by means of a coal furnace 15, upon which the casing extension 8 rests.

Each header is provided with a vertical extension 16, in which is fitted and supported an arcuate plate 17, which is fitted to and supports the under side of the boiler 1.

Embracing the boiler 1 are two arcuate members 18, which are T-shaped in cross section and which are provided each with a laterally extending flange 19, which engages the inner side of the casing 6 and holds the latter in spaced relationship to the boiler 1.

A conductor 20 has one end connected to the steam dome 2, the other end being connected to the left header member 9, as viewed in Fig. 1, the conductor 20 is provided with a vertical condensing coil 21, located in a condensing tank 22, which has connected to its bottom an intake water pipe 23, provided with a shut-off valve 24. The conductor 20 intermediate of the dome 2 and tank 22 is provided with a shut-off valve 25.

The condensing coil 21 is arranged so that steam from the boiler dome 2 passes downwardly through and is condensed in the coil 21.

The conductor 20 intermediate of its discharge end and the tank 22 is provided with an outlet for distilled water, preferably comprising a branch pipe 26 which discharges downwardly into a distilled water container 27, near the bottom thereof. The container 27 is provided near its bottom with a draw-off cock 28. The upper end of the container 27 is provided with an air vent comprising a vertical tube 29, the upper end of which discharges to the atmosphere and the lower end of which communicates interiorly with the container 27. In the container 27 is a float valve 30 having an upwardly extending stem 31 which extends

through the tube 29 and serves as a guide for the valve. To the upper end of the stem 31 is secured a disk 32, which is adapted to rest upon the upper end of the tube 29 so 5 as to support the valve 30.

The conductor 20 intermediate of the branch 26 and the discharge end of the conductor is provided with a check valve 33 of any ordinary construction, which opens 10 toward the discharge end of the conductor 20.

Extending upwardly through the bottom of the tank 21 to near the top thereof is a conductor 34 which serves to carry off the 15 overflow of hot water from the tank 22 and which is provided with two discharge branches 35 and 36 provided respectively with a shut-off valve 37 and a check valve 38. The branch 36 is connected with the 20 right header member 9, as viewed in Fig. 1, and discharges interiorly into the right header. The check valve 38 may be of any ordinary construction, so long as it opens 25 toward the header to which the branch 36 is connected.

In Fig. 3, is illustrated a check valve adapted to be employed in the branch 36. Referring to Fig. 3, 39 designates a vertically slidabale valve adapted to rest by 30 gravity upon a seat 40 in the casing of the check valve 38. The hot water from the tank 22 will flow through the conductor 34 and through the branch 36 and lift the valve 39 and pass into the adjacent header, when 35 the valve 37 is closed. If the valve 37 is opened, the boiler pressure will close the check valve 39 and hot water will be discharged through the branch 35 for such purposes as may be desired, as for heating hot 40 water radiators or for bathroom or kitchen purposes.

The boiler 1 has connected to it near its upper side and at one end a steam pipe 40 provided with a shut-off valve 41. By opening 45 the valve 41, steam may be supplied by the pipe 40 for any desired purpose.

When the tubes 13 are heated by the gaseous products of combustion from the burner 14 or the furnace 15, the flow of 50 water through the tubes 13 will be to the left as viewed in Fig. 1, so that water in the right header will pass through the tubes 13 to the left header and thence through the pipe 12, which is at the left, into the boiler 55 1, the water returning from the boiler into the right header through the right pipe 12. The boiler may be replenished with hot water from the tank 22 by means of the overflow conductor 34 and branch 36, by opening 60 the valve 24 and closing the valve 37, as already described.

Steam forming in the boiler 1 will enter the dome 2 and will pass therefrom, when the valve 25 is opened, through the conductor 20 and downwardly through the con-

densing coil 21, in which the steam will be condensed to form distilled water, which will pass by the conductor 20 and the branch 26 into the distilled water container 27, until the float valve 30 is lifted and closes the vent 70 pipe 29, at which time the check valve 33 will open, thus permitting distilled water to be automatically discharged into the left header, as viewed in Fig. 1, when water is not passing through the branch 26 into the 75 container 27 to replace distilled water drawn from the container 27 through the draw-off cock 28. When the latter is opened, distilled water is discharged therethrough, upon which the float valve 30 lowers and distilled water passes into the container 27 through the branch 26, the check valve 33 80 at such time being closed by boiler pressure.

By having the gaseous products of combustion pass between the tubes 13 and 85 around the boiler 1, and dome 2, a maximum of heating efficiency is afforded.

By having the steam pass downwardly through the coil 21, the hottest water in the tank 22 is supplied to the boiler by means 90 of the overflow conductor 34.

I do not limit my invention to the structure shown and described, as modifications, within the scope of the appended claims, may be made without departing from the 95 spirit of my invention.

What I claim is:—

1. In a distilling and heating apparatus, a boiler, a conductor connected at its ends respectively with the boiler above and below the water line thereof and having a valved outlet, a check valve in the conductor, opening toward the boiler, intermediate of the outlet and the discharge end of the conductor, and means for condensing steam in 10 said conductor intermediate of the intake end thereof and said outlet.

2. In a distilling and heating apparatus, a boiler, a conductor connected at its ends respectively with the boiler above and below 11 the water line thereof and having an outlet comprising a distilled water container having a draw-off cock, a check valve in said conductor, opening toward the boiler, intermediate of said outlet and the discharge 11 end of said conductor, and means intermediate of the outlet and the intake end of the conductor for condensing steam in the latter.

3. In a distilling and heating apparatus, a boiler, a conductor connected at its ends 12 respectively with the boiler above and below the water line thereof and having an outlet comprising a distilled water container having a draw-off cock and an air vent and a valve for closing said vent, a check valve in 12 said conductor, opening toward the boiler, intermediate of the outlet and the discharge end of the conductor, and means intermediate of the outlet and the intake end of the conductor for condensing steam in the latter. 13

4. In a distilling and heating apparatus, a boiler, a conductor connected at its ends respectively with the boiler above and below the water line thereof and having an outlet comprising a distilled water container having a draw-off cock, an air vent and a float valve for closing said vent, a check valve in the conductor, opening toward the boiler, intermediate of the outlet and the discharge end of the conductor, and means intermediate of the outlet and the intake end of the conductor for condensing steam in the latter.

5. In a distilling and heating apparatus, a boiler, a water supply conductor having two discharge branches, one having a shut-off valve, and the other discharging into the boiler and having a check valve opening toward the boiler, a tank from which said conductor carries off the overflow and a conductor connected with the boiler above the water level thereof and discharging into the boiler below the water level thereof and arranged to heat the water in said tank.

6. In a distilling and heating apparatus, a boiler, a water supply conductor having two discharge branches, one having a shut-off valve, and the other discharging into the boiler and having a check valve opening toward the boiler, a tank in which said conductor carries off the overflow, and a conductor connected with the boiler above the water level thereof and discharging into the boiler below the water level thereof and having a condensing coil located in said tank.

7. In a distilling and heating apparatus, a boiler, a water supply conductor having two discharge branches, one having a shut-off valve, and the other discharging into the boiler and having a check valve opening toward the boiler, a tank from which said conductor carries off the overflow, and a conductor connected with the boiler above the water level thereof and discharging into the boiler below the water level thereof and having a condensing coil located in said tank through which the flow passes in a downward direction.

8. In a distilling and heating apparatus, a boiler, a water supply conductor having two discharge branches, one having a shut-off valve, and the other discharging into the boiler and having a check valve opening toward the boiler, a tank from which said conductor carries off the overflow, and a conductor connected with the boiler above the water level thereof and discharging into the boiler below the water level thereof and

arranged to heat the water in said tank and having a valved outlet and a check valve intermediate of said outlet and the discharge end of the last named conductor and opening toward the boiler.

9. In a distilling and heating apparatus, a boiler, a water supply conductor having two discharge branches, one having a shut-off valve, and the other discharging into the boiler and having a check valve opening toward the boiler, a tank from which said conductor carries off the overflow, and a conductor connected with the boiler above the water level thereof and discharging into the boiler below the water level thereof and arranged to heat the water in said tank, and having a valved outlet, a check valve between the outlet and the boiler opening toward the boiler, the outlet comprising a distilled water container having a shut-off cock.

10. In a distilling and heating apparatus, a boiler, a water supply conductor having two discharge branches, one having a shut-off valve, the other discharging into the boiler and having a check valve opening toward the boiler, a tank from which said conductor carries off the overflow, and a conductor connected with the boiler above the water level thereof and discharging into the boiler below the water level thereof and arranged to heat the water in said tank, and having a valved outlet, a check valve between the outlet and the boiler opening toward the boiler, the outlet comprising a distilled water container having a shut-off cock and a vent for air, and a float valve for closing said vent.

11. In a distilling and heating apparatus, a boiler, a water supply conductor having two discharge branches, one having a shut-off valve, the other discharging into the boiler and having a check valve opening toward the boiler, a tank from which said conductor carries off the overflow, and a conductor connected with the boiler above the water level thereof and discharging into the boiler below the water level thereof and having a coil located in said tank and provided with a valved outlet, a check valve between the outlet and the boiler opening toward the boiler, the outlet comprising a distilled water container having a shut-off cock and an air vent, and a float valve for closing said vent.

In testimony whereof I have signed my name to this specification.

ROBERT S. MEARS.
